ENGINE FRAME

Filed April 13, 1931

UNITED STATES PATENT OFFICE

ABRAHAM G. BUWALDA, OF PELLA, IOWA, ASSIGNOR TO WOODROW WASHING MACHINE COMPANY, OF PELLA, IOWA, A CORPORATION OF IOWA

ENGINE FRAME

Application filed April 13, 1931. Serial No. 529,880.

The object of my invention is to provide a simple, durable and inexpensive frame construction adapted to brace the lower ends of washing machine legs, and at the same time provide improved means for supporting an engine of the internal combustion type, in such a manner that the engine may be easily and quickly removed when so desired, and to decrease the vibration of the washing machine to which the bracing frame is connected.

A further object is to provide improved means for mounting an engine frame to a washing machine frame so that the engine may be easily and quickly removed, and whereby a portion of the weight of the engine may be carried by suitable casters while being removed.

My invention consists in the construction, arrangement and combination of the various parts of the device, whereby the objects contemplated are attained, as hereinafter more fully set forth, pointed out in my claims, and illustrated in the accompanying drawing, in which:

Figure 1 is a plan view of my improved engine frame.

Figure 2 is a front elevation of same.

Figure 3 is a side elevation of my improved frame.

Figure 4 is an enlarged, detail, sectional view taken on the line 4—4 of Figure 1.

Figure 5 is an enlarged, detail, sectional view taken on the line 5—5 of Figure 1.

Figure 6 is a detail sectional view taken on the line 6—6 of Figure 1.

Figure 7 is a bottom view of the means for detachably mounting the inner end of the engine frame with the main frame.

Referring to the accompanying drawing, I have used the reference numeral 10 to indicate the legs of a washing machine tub, the upper portion of the legs and tub being broken away and not illustrated inasmuch as they form no part of my present invention.

The legs 10 are preferably formed of angular sheet metal and have their lower ends braced by means of a horizontally arranged frame 11 formed substantially triangular and having side members 12 and a front member

13. The angles 12 are connected near their central portions by means of an angle iron 14 having an upwardly extending flange 15.

The angle 14 is parallel with the front members 13. The front members 13 are 65 formed comparatively short so that a space 16 is provided between the inner ends of the members 13.

The inner ends of said members 13 are connected to angle irons 17 which are 60 extended rearwardly, having their rear ends connected to the inner surface of the angle 14 by means of bolts or rivets 18. The angles 12 and 13 are permanently fixed to the lower ends of the leg members 10. Said frame 11 65 is carried by suitable casters 19.

By this construction it will be seen that a recess 20 is formed in the front side of the frame member in which an engine frame or base 21 is mounted. Said base 21 supports 70 the ordinary internal combustion engine 22, such as employed for operating washing machines.

Connected beneath the front edge of the base 21 is a bar 23, said bar being permanently fixed to the base. Near each end of the bar 23 is a caster cup 24 for receiving the stem 25 of a caster 26. By this arrangement it will be seen that the front end of the engine is mounted on caster wheels which 80 rest on the floor. The weight of the front end of the engine is carried thereby.

The back end of the engine base is provided with a pair of rearwardly projecting arms 27 provided with slots 28, each slot being 85 designed to receive an upwardly projecting bolt 29 having a washer 30 below the member 27 and a washer 31 above the member 27. Each bolt 29 projects upwardly through an opening 32 in the frame member 14. A 90 spring 33 is supported on the washer 31 and beneath the frame member 14, while a spring 34 rests on the upper face of the horizontal flange of the member 14 and beneath a washer 35, which rests against the nut 36 carried by 95 the upper end of the bolt.

By this arrangement it will be seen that yieldable pressure is applied to the washers 30 and 31 tending to close them together, and provides means for frictionally retaining the 100

members 27 in position. The weight of the rear end of the base 21 is carried by the upper spring 34, while the spring 33 deadens any upward movements of the rear end of the engine base.

By this arrangement it will be seen that the engine base may be easily detached by simply moving the base forwardly, causing the members 27 to be disengaged from between the washers 30 and 31. The edges of said washers are turned outwardly to permit the members 27 to be forced into position between said washers by simply moving the engine base rearwardly, said engine base being held to its rearward position of movement by the tension of the driving belt which is applied to the pulley 37.

A yieldable belt tightener is mounted on the back face of the flange 15. Said tightener comprises a bar 38 having one end bent forwardly and designed to engage the rear face of said flange. The other end of said bar 38 is provided with a forwardly extending pin 39 which projects through an opening in the flange 15 and engages the rear edge of the engine base. A bolt 40 is mounted in said flange and projects rearwardly through the bar 38 and provided with a spring 41, which is held in position on the bolt 40 by means of a nut 42. The spring 41 applies yieldable forward pressure to the rear end of the engine frame.

Supported on the upper surface of each end of the bar 23 is a spring supporting lug 43 on which a spring 44 is supported. The upper end of the spring 44 engages the under surface of a bracket 45 carried by the inner end of the frame members 13. The said bracket 45 is provided with an opening 46 in which a bolt 47 is mounted. The lower end of said bolt is screw threaded into the member 43. The spring 44 is of such length and tension that downward pressure is imparted to the member 43 and to the bar 23, thereby yieldably loading the forward end of the engine base to prevent chattering of the casters 26 on the floor on which the base is supported.

The head of the bolt 47 supports the members 43 when the frame member 23 is removed. The members 43 are frictionally retained on the top surface of the member 23 to permit the said base 21 to be adjusted forwardly to maintain a constant belt pressure.

Thus it will be seen that I have provided a supporting frame for an internal combustion engine of the vertical type, which is so constructed that the engine base may be easily and quickly removed from the main frame member for repairs or for using the engine for other power purposes, and at the same time I have provided means whereby the engine base will be supported in operative relation with the washing machine frame, and whereby all excessive vibration is elimi-

nated from the washing machine, which is particularly desirable in the modern washing machine constructions in which the washing machine tub and legs are formed of comparatively light sheet metal, of which there is not sufficient weight to steady the ordinary internal combustion engine.

I claim as my invention:

1. In a device of the class described, the combination of a supporting frame having one side formed with a recess, an engine base within said recess, casters supporting the outer end of said engine base, means carried by said frame for yieldably supporting the inner end of said engine base against upward and downward movement, and means carried by the frame for yieldably applying downward pressure to the outer end of said engine base.

2. In a device of the class described, the combination of a supporting frame having one side formed with a recess, an engine base within said recess, casters supporting the outer end of said engine base, means carried by said frame for yieldably supporting the inner end of said engine base against upward and downward movement, means carried by the frame for yieldably applying downward pressure to the outer end of said engine base, and means for frictionally and detachably connecting the inner end of said engine base and said yieldable supporting means.

3. In a device of the class described, the combination of a supporting frame, an engine base, casters supporting one end of said engine base, means for yieldably supporting the opposite end of said engine base to said frame, and means for applying yieldable downward pressure to the caster supporting end of said engine base from said frame.

4. In a device of the class described, the combination of a substantially triangularly shaped frame member having one side provided with a recess comprising inwardly projecting frame members and a transversely arranged frame member, an engine base supported within said recess, inwardly projecting arms carried by said engine base supported beneath said transversely arranged frame member, springs above and below said inwardly projecting arms, a bolt for carrying said arms from the upper springs, casters supporting the outer end of said engine base, and means carried by the frame members adjacent to the outer end of said engine base for applying yieldable downward pressure to the outer end of said engine base.

5. In a device of the class described, the combination of a substantially triangularly shaped frame member having one side provided with a recess comprising inwardly projecting frame members and a transversely arranged frame member, an engine base supported within said recess, inwardly projecting arms carried by said engine base sup-

ported beneath said transversely arranged frame member, springs above and below said inwardly projecting arms, a bolt for carrying said arms from the upper springs, and 5 casters supporting the outer end of said engine base.

6. In a device of the class described, the combination of a supporting frame, an engine base within the frame, casters supporting 10 one end of said engine base, means for yieldably supporting the opposite end of said engine base to said frame, and means for applying yieldable downward pressure to the caster supporting end of said engine base 15 from said frame.

7. In a device of the class described, the combination of a supporting frame having one side formed with a recess, an engine base within said recess, casters supporting the 20 outer end of said engine base, means carried by said frame for yieldably supporting the inner end of said engine base, and means for moving the said engine base inwardly and outwardly relative to said supporting frame.
